UNITED STATES PATENT OFFICE

2,456,535

UNIVERSAL ALL WIRE BRACKET

Raymond R. Rundell, Miami, Fla.

Application October 8, 1945, Serial No. 621,140

7 Claims. (Cl. 248—302)

1

This invention relates to resilient article holders for supporting one or more articles from a wall or other support.

An object of this invention is to provide an article holder which is formed out of a single strand of resilient wire which is bent to form a bracket or article support.

Another object of this invention is to provide a holder of this kind which includes a pair of article clamping jaws and a base upon which the article is adapted to rest.

A further object of this invention is to provide a holder of this kind wherein the base on which the article rests is formed integral with the resilient jaws.

A further object of this invention is to provide a holder of this kind wherein the resilient jaws may include loops or eyes for receiving suspended articles, such as toothbrushes or the like.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a detailed side elevation of an article holder constructed according to an embodiment of this invention.

Figure 2 is a detailed front elevation of the device.

Figure 3 is a plan view of the device.

Figure 4 is a detailed side elevation of a modified form of this device.

Figure 5 is a rear elevation of the structure shown in Figure 4.

Figure 6 is a plan view of the structure shown in Figures 4 and 5.

Figure 7 is a sectional view taken on the line 7—7 of Figure 4.

Figure 8 is a plan view partly in section of another modification of this invention.

Figure 9 is a plan view of another modification of this invention.

Figure 10 is a detailed side elevation of a further modification of this invention.

Figure 11 is a front elevation of the structure shown in Figure 10.

Figure 12 is a top plan of the structure shown in Figures 10 and 11.

Figure 13 is a detailed side elevation of a further modification of this invention.

2

Figure 14 is a plan view partly broken away of the structure shown in Figure 13.

Figure 15 is a rear elevation of the structure shown in Figures 13 and 14.

Figure 16 is a plan view of another modification of this invention.

Figure 17 is a detailed side elevation of the structure shown in Figure 16.

Figure 18 is a detailed rear elevation of the structure shown in Figures 16 and 17.

Referring to the drawings and first to Figures 1, 2, and 3, the numerals 20 and 21 designate a pair of confronting substantial V-shaped jaw members which are formed at the angle between the sides thereof with eyes 22 and 23 respectively.

The forward end of the jaw 20 terminates in an eye 24 and the forward end of the jaw 21 terminates in an eye 25. The rear end of the jaw 20 terminates in a coil 26, the upper end of which is formed into a loop 27. The end of the loop 27 has a downwardly extending bar 28 which extends through the center of the coil 26. The rear end of the jaw 21 has extending upwardly therefrom a coil 29 and a loop 30 extends upwardly from the coil 29 and terminates in a downwardly extending bar 31 which extends through the center of the coil 29.

The bars 28 and 31 have extending from the lower ends thereof right angularly disposed bars 32 and 33 respectively which terminate in a relatively large base-forming coil 34.

Referring now to Figures 4, 5 and 6, the numerals 35 and 36 designate a pair of V-shaped jaws which have eyes 37 and 38 formed integral with the rear ends thereof. The forward end of the jaw 35 has extending downwardly therefrom a bar 39 and the forward end of the jaw 36 has extending downwardly therefrom a bar 40. The lower end of the bar 39 has extending rearwardly and laterally therefrom a base-forming bar 41 and the lower end of the bar 40 has extending rearwardly and laterally thereof a second base-forming bar 42 which crosses the bar 41.

The rear end of the bar 41 has extending inwardly therefrom a bar 43 terminating in a vertically disposed coil 44. The rear end of the bar 41 has extending inwardly therefrom a bar 45 terminating in a vertically disposed bar 46. The bar 46 is continued upwardly as indicated at 47 and is then formed into a loop or eye 48.

The upper end of the coil 44 is continued upwardly and outwardly as at 49 and terminates in a loop or eye 50. The loops or eyes 48 and 50 are connected together by a straight upper bar 51.

Referring now to Figure 8, there is disclosed

another form of this invention which includes a pair of jaw members 52 and 53 of substantial V-shape and which are formed at the rear ends with eyes 54 and 55. The jaw member 52 is formed at its forward end with a downwardly extending bar 56 and the jaw member 53 is formed at its forward end with a downwardly extending bar 57. An eye 58 designed for receiving a tooth-brush or the like is right angularly disposed from the lower end of the vertical bar 56 and a similar eye or loop 59 is right angularly disposed and extends from the lower end of the vertical bar 57.

A pair of crossed rearwardly extending base-forming bars 60 and 61 extend from the eyes 58 and 59 and are connected together to a supporting structure similar to the structure shown in Figure 5 including the coil 62 and an upper loop bar 63 similar to the bar 51 with the loops or eyes 48 and 50.

Referring now to Figure 9, there is disclosed a bracket or clamping structure confronting V-shaped jaw members 64 and 65 which have extending from the forward ends thereof vertical bars 66 and 67. Rearwardly extending crossed bars 68 and 69 extend from the lower ends of the vertical bars 66 and 67 and inwardly extending bars 70 and 71 extend from the rear divergent ends of the bars 68 and 69. A vertically disposed coil 72 extends upwardly from the inner end of the bar 70 and a vertically disposed bar 73 formed integral with the bar 71 extends through the coil 72. In other respects, the construction shown as to the loops 48 and 50 in Figure 5 is used at the upper ends of the coil 72 and the bar 73.

The rear ends of the jaws 64 and 65 are provided with loops 74 which engage about the coil 72 so as to anchor the rear ends of the jaws 64 and 65 and provide for pivotal movement thereof.

Referring now to Figures 10, 11 and 12, the numerals 75 and 76 designate a pair of confronting V-shaped jaws which are formed at the outer ends with eyes 77 and 78. The inner ends of the jaws 75 and 76 are formed with vertically disposed coils 79 and 80 which have eyes 81 and 82 respectively extending upwardly therefrom. The eyes 81 and 82 have extending downwardly therefrom vertical bars 83 and 84 respectively, and the lower ends of the bars 83 and 84 terminate in convergent extensions 85 and 86. The extensions 85 and 86 are twisted together, as at 87, and these bars are then extended downwardly, as indicated at 88 and 89 respectively. Forwardly extending base-forming bars 90 and 91 extend from the lower ends of the bars 88 and 89 and upwardly directed lug-forming loops 92 and 93 are formed at the forward ends of the arms or bars 90 and 91.

A U-shaped rearwardly extending member 94 extends from the inner ends of the loops 92 and 93 and is disposed between the bars 90 and 91. The upwardly directed members 92 and 93 provide a means for holding the tumbler or article against forward movement on the base of the bracket.

Referring now to Figures 13, 14 and 15, there is disclosed a bracket structure including a pair of confronting V-shaped jaws 95 and 96 having eyes 97 and 98 in the angle thereof and also having outer eyes 99 and 100 adapted to receive a toothbrush or another article. The eyes 97 and 98 may also receive brushes or similar articles.

The rear end of the jaw 95 is formed with a vertically disposed bar 101 and the rear end of the jaw 96 is formed with an elongated coil 102. The lower ends of the bar 102 and the coil 103 terminate in lateral extensions 103 and 104

respectively and the extensions 103 and 104 have extending laterally therefrom loops 105 and 106 respectively. A pair of downwardly extending bars 107 and 108 extend from the loops 105 and 106 and forwardly extending bars 109 and 110 extend from the lower ends of the bars 107 and 108. Upwardly inclined retaining members 111 and 112 are formed integral with the forward ends of the base bars 109 and 110 extending inwardly toward each other and a pair of rearwardly extending divergent bars 113 and 114 extend from the inner ends of retaining members 111 and 112 respectively. The rear ends of the bars 113 and 114 are connected together by a curved connecting bar 115.

Referring now to Figures 16, 17 and 18, there is disclosed another form of bracket including a pair of confronting V-shaped jaw members 116 and 117. The rear end of the jaw 117 terminates in a vertically disposed coil 118 and the rear end of the jaw 116 terminates in a vertical bar 119 extending through the coil 118. Laterally extending bars 120 and 121 extend from the coil 118 and bar 119 and terminate in eyes 122 and 123.

The forward ends of the jaws 116 have extending downwardly therefrom a front bar 124 and the forward end of the jaw 117 has extending downwardly therefrom a front bar 125. The lower end of the front bar 124 has extending rearwardly and outwardly therefrom a bar 126 which is connected to a forwardly extending inner bar 127 by a curved connecting member 128.

The forward end of the bar 127 has extending obtusely therefrom a bar 129 and the latter is reverted at its inner end and extended rearwardly to form a bar 130. The bars 127 and 130 form base bars on which the article engaged with the jaws is adapted to rest. The rear end of the bar 130 has extending inwardly therefrom a bar 131 and a coil 132 extends downwardly from the bar 131. The lower end of the front bar 125 has extending rearwardly and outwardly a bar 133 and an obtusely disposed bar 134 extends from the rear end of the bar 133. A right angularly disposed bar 135 is formed integral with the rear end of the bar 133 and the bar 135 is reversed to form a rear bar 136 which terminates in an inwardly extending bar 137.

The bar 137 is formed with a downwardly extending bar 138 which extends through the coil 132 and forms an elongated loop 139 for receiving a fastening device or the like. The eyes 122 and 123 and the loop 139 are rearwardly offset from the coils 118 and 132 as shown more clearly in Figure 17.

What I claim is:

1. A wire bracket comprising a pair of crossed base-forming members, a pair of confronting V-shaped article-gripping jaw members, means integral with the forward ends of said base-forming members and said jaw members supporting the latter above said base-forming members, confronting extensions carried by the rear ends of said base-forming members, a vertical bar integral with one extension, a resilient coil integral with the other extension and engaging about said bar, and a right angularly disposed looped supporting member integral with said coil and said bar.
2. A wire bracket as set forth in claim 1 wherein the rear end of said jaw members include eyes loosely engaging about said coil.
3. A wire bracket comprising a pair of horizontal outwardly convergent base bars, a U-shaped inner base member between said bars, upwardly

extending stop members connecting the outer ends of said bars with the free outer ends of said U-shaped member, a pair of vertical supporting bars integral with the rear ends of said first bars, said supporting bars including a twisted intermediate portion and spaced upper and lower portions, a pair of V-shaped confronting jaws, and means resiliently supporting said jaws from the upper portion of said supporting bars.

4. A wire bracket as set forth in claim 3 wherein said latter named means includes a coil loosely engaging about the upper portion of a supporting bar and integral with the rear end of a jaw.

5. A wire bracket comprising a pair of vertical supporting bars, a circular base extending forwardly of the lower ends of said bars, a pair of confronting V-shaped jaw members, and means resiliently securing said jaw members to said bars adjacent the upper ends of the latter, each jaw including a loop at the apex of the V.

6. A wire bracket comprising a pair of base forming members, a pair of confronting V-shaped article gripping jaw members, means integral with said base forming members and said jaw members supporting the latter above said base forming members, confronting extensions carried by the rear ends of said base forming members, a vertical bar integral with at least one extension, a resilient coil integral with another extension

and engaging about said bar, and a looped supporting member integral with said coil and said bar, said looped member being disposed perpendicular to the axis of said coil.

- 5 7. A wire bracket comprising a pair of crossed base forming members, a pair of confronting V-shaped article gripping jaw members, means integral with said base forming members and said jaw members supporting the latter above said base forming members, confronting extensions carried by the rear ends of said base forming members, a vertical bar integral with at least one extension, a resilient coil integral with another extension and engaging about said bar, and 10 a looped supporting member integral with said coil and said bar, said looped member being disposed perpendicular to the axis of said coil.

RAYMOND R. RUNDELL.
